We claim the ornamental design for a multifunctional mobility system base, as shown and described.

DESCRIPTION

FIG. 1 is a perspective view of a multifunctional mobility system base showing our new design;

FIG. 2 is a front view thereof;

FIG. 3 is a rear view thereof;

FIG. 4 is a side view thereof;

FIG. 5 is a side view of the opposite side of FIG. 4;

FIG. 6 is a top view thereof; and,

FIG. 7 is a bottom view thereof.

The broken lines shown in the drawings illustrate portions of the multifunctional mobility system base that forms no part of the claimed design.
